Primary Examiner — R. Johnson(74) *Attorney, Agent, or Firm* — Kathryn Perales(57) **CLAIM**

The ornamental design for a classical guitar support as shown and described.

DESCRIPTION

FIG. 1 is a front perspective view of a classical guitar support showing my new design;

FIG. 2 is a front elevation view thereof;

FIG. 3 is a rear elevation view thereof;

FIG. 4 is an enlarged right-side elevation view thereof;

FIG. 5 is an enlarged left-side elevation view thereof;

FIG. 6 is a top plan view; and,

FIG. 7 is a bottom plan view thereof.

The broken lines represent the portions of the design that form no part of the claim.
